SUPPORTING MECHANISM FOR
LOCOMOTIVES

Frank B. Barclay, Chicago, Ill.

Application July 21, 1934, Serial No. 736,304

8 Claims. (Cl. 105—82)

This invention relates to the spring supporting mechanism for railway locomotives.

One of the objects of the invention is the provision of new and improved means for supporting a locomotive from the trucks whereby shocks and vibration of the mechanism will be reduced to a minimum.

Another object of the invention is the provision of a shock absorbing mechanism for locomotives that may be readily applied to the conventional locomotive at a minimum of time and expense.

A still further object of the invention is the provision of new and improved supporting mechanism for locomotives that will efficiently absorb violent shocks and vertical vibrations of the same which is simple in construction, efficient in operation, easily installed and not likely to become broken or out-of-repair.

Other and further objects and advantages of the invention will appear from the following description, taken in connection with the accompanying drawings, in which

Figs. 1a and 1b are side elevations of a locomotive with parts broken away;

Fig. 2 is a side elevation of a spring supporting bar and spring for the front truck equalizer shown on an enlarged scale;

Fig. 3 is a top plan view thereof;

Fig. 4 is a section on the line 4—4 of Fig. 2;

Fig. 5 is a side elevation of an equalizer member with the invention in position thereunder, shown on an enlarged scale;

Fig. 6 is a top plan view thereof;

Fig. 7 is a section on the line 7—7 of Fig. 5;

Fig. 8 is a side elevation of a portion of a locomotive showing the application of a modified form of the invention;

Fig. 9 is a section on the line 9—9 of Fig. 8;

Fig. 10 is a side elevation of the construction shown in Fig. 9, with parts in section;

Fig. 11 is a section on the line 11—11 of Fig. 10.

It is common practice in locomotives to provide a system of load equalizing mechanism for distributing the load or weight of the locomotive and associated mechanism to all of the axles whereby the individual axles will not be placed under excessive strain when the trucks of the locomotive pass over an uneven road bed. This equalizing mechanism is usually provided with heavy springs which do not readily absorb a very large amount of the shock, due to their stiffness, and, as a consequence, vibration and shocks incident to high speeds over the inequalities in the road are transmitted to the mechanism, and are very detrimental thereto.

The present invention seeks to eliminate these defects by the provision of mechanism that will absorb the shocks and vibration to which the locomotive is subjected under normal operating conditions. The parts are so constructed that

light shocks will be resisted by springs of much smaller capacity than the conventional springs used on locomotives, but the more violent shocks will be absorbed by the shock absorbing mechanism which reinforces the capacity of the springs. 5

In the use of the stiff springs commonly employed on locomotives, the inertia of the parts during shocks is not properly absorbed, and, as a consequence, there is unnecessary wear on the moving parts, a tendency to loosen the operating mechanism and, in some cases, to cause crystallization and a consequent weakening of the parts. 10

Referring now to the drawings, the reference character 10 designates generally a locomotive comprising a boiler 11, supporting frame 12 and various accessories. The locomotive is carried by the front truck 13, comprising a suitable frame and front truck supporting wheels 14, the driver truck 15, comprising a suitable frame and the driver wheels 16 and the trailer truck 17 comprising a suitable frame and the trailer truck supporting wheels 18, as is usual in such constructions. Any suitable number of driver wheels may be employed. In the form of construction shown, the locomotive is of the type having four driver 20 wheels on each side. 25

A suitable load equalizing mechanism 19 is employed for distributing the load to the axles of the locomotive trucks. This mechanism may be of the usual or well-known type in which the present invention is substituted for the usual supporting springs. This mechanism comprises a plurality of pivoted elements or driver equalizers 21 which are pivotally connected to the frame 12 of the locomotive. These elements are connected to supporting members or driver equalizer bars 22 located above the axles 23 of the drive wheels by means of the links 24. There are four of the driver bar equalizers, one above each axle, as shown on the drawings. A driving box saddle 40 25 rigidly secured to the journal box 26 extends upwardly from each axle and its upward end is recessed for receiving a corresponding projection 27 on the base 28 of the spring and shock absorber unit or assembly 29. 30 35 45

The assembly 29 may be so constructed that it may be substituted in existing structures for the driver and equalizer springs at present employed.

Since the arrangement of the spring and shock 50 absorber assembly and its attachment to the equalizer mechanism is the same for each driver wheel, only one need be described. This assembly comprising the base plate 28 (see Fig. 5) is provided with spring seats 31 in which are seated 55 a plurality of compression springs 32. These springs are seated at their upper ends in corresponding seats in the equalizer bar 22. The parts are so constructed that the conventional elliptical spring may be removed and the spring and 60

absorbing unit substituted therefor. For this reason, the bar 22 is preferably bowed upwardly for accommodating the spring assembly 29 without necessitating any changes in the length of the links 24.

A suitable shock absorbing member or unit 33 on the assembly 29 is provided for assisting in absorbing the shocks incident to the running of the locomotive. This unit may be of any suitable construction. The details of the same constitute no part of the present invention, and, as shown, comprises a base 30 shown in detail in Fig. 11 and a standard 34 having the inclined wedging faces 35 thereon. The faces 35 are adapted to be engaged by a plurality of wedge members 36 which have inclined faces 37 cooperating with the wedge faces 35. The lower ends of the wedge members 36 are flanged outwardly, as at 40, and an annular spring seat 37 is seated thereon. The wedge members 36 are adapted to be frictionally engaged by the friction shoes 38 having each inclined inner surfaces 39 for frictionally engaging the exterior of the wedge members 36. A friction spring 41 seated on the annular spring seat 37 surrounds the shoes and frictionally engages the same. An annular seat 42 surrounds the shoes 38 and is engaged by the upper end of the spring 41. This annular seat in turn engages the flanges 43 on the shoes 38.

30 During the compression of the shock absorbing unit, the shoes 38 are forced downwardly and this, in turn, by its frictional engagement with the wedge members 36, will cause said wedge members to engage the wedge surface 35 for forcing the shoes outwardly for increasing the friction between said shoes and the friction spring 41. The compression of the unit will meet with increased resistance due to the wedging action of the parts, thereby gradually absorbing the 40 shocks which may be delivered thereto. There is at least one of these shock absorbing units above each of the axles.

The equalizing mechanism may be, and preferably is, extended to the trailer truck through 45 the driver and trailer truck equalizer 44, the forward end of which is connected to the hanger 45 of the equalizing mechanism and the rear end of which is connected to a hanger 46 at its lower end.

50 The upper end of the hanger 46 is pivotally connected to a supporting member, or equalizer bar, 47, the rear end of which is pivotally connected to the hanger 48 which in turn is pivotally connected as at 49 to the rear end of the frame 12. Interposed between the trailer truck axle 52 and the equalizer bar 47 is a spring and shock absorbing unit or assembly 29 which may be of the same type as that described above.

The front truck, as shown, is provided with 60 a separate equalizing mechanism from the driver truck, but it is understood that the driver truck equalizing mechanism may be extended to include the front truck. In the form shown, equalizer bars 53 of the usual construction, have their ends resting on the journal boxes 54 of the axles 55 and 56 of the front truck. A spring supporting and shock absorbing unit, similar to that described above, is adapted to be inserted between the spring bracket 58 and the equalizer bars 53 at each side of the truck. In the conventional type of construction, a leaf spring is usually supported by the bars 53 which, in turn, is connected to the bracket 58. In the present construction, this spring may be removed and 70 spring supporting member 59 may be substituted

therefor. This member is shown enlarged in Fig. 2 and is provided at each end thereof with openings 61 and 62 for connecting the same to the equalizer bars 53. The central portion of the member 59 is depressed and is provided with seats 63 in which the spring units 64 and 65 and shock absorbing unit 66 are adapted to seat.

A suitable cap member 61 having seats 68 on its under side for receiving the upper ends of the springs 64 and 65 and spring unit 66 has an upwardly extending projection 69 convex on its upper end which is adapted to engage a corresponding recess in the lower end of the bracket 58, which, in turn, is rigidly connected to the frame 12.

15 It will thus be seen that a spring and shock absorbing unit may be substituted for the conventional driver springs usually employed and one is also substituted for the supporting spring on both the front and trailer trucks. These units 20 are so constructed that they may be substituted for these springs without any modification whatever to the remaining parts of the equalizer mechanism.

The form of construction shown in Figs. 8, 9, 25 10 and 11 differs from that described in that the spring supporting and shock absorbing unit 79 is applied at a different place. In this construction, it is interposed between the driver equalizers 71 and the hangers 72. In the form of construction shown, a pair of hangers 72, one at each side 30 of the unit is provided. The base 80 of the unit is provided with an opening 73 to which the lower ends of the hangers 72 are connected, as by bolts 74. The cap plate 75 of the unit is provided with 35 a recess or bearings 76 in which a projection 77 on the end of the spring equalizer 71 is adapted to engage. The base and cap plates are recessed, as at 78 and 79 for receiving the hangers 72, as clearly shown in Figs. 8 and 9, whereby the unit 40 is held in upright position.

One of these units may be inserted between each hanger and the spring equalizer if desired, so there will be two of these units for each axle, or a single unit for each axle may be employed, 45 as disclosed in the drawing.

In this arrangement the usual springs may be retained, it being necessary only to substitute the equalizers 71. The equalizers 71 are bent upwardly at their ends for accommodating the 50 spring and shock absorber units without increasing the lengths of the hangers 72.

While I have disclosed a particular type of spring supporting and shock absorbing unit, it is understood that other types may be employed in 55 connection with the equalizing system. By means of this arrangement, minimum shocks will be absorbed by the springs which are of less capacity than the conventional springs and the severer shocks will be absorbed by the shock absorbing 60 units. In this way, the locomotive and associated parts will be relieved of the abrupt shocks to which they are subjected with the present equipment and as a consequence the life of the parts will be greatly extended.

65 I claim as my invention:

1. In combination, a locomotive, truck members beneath said locomotive, said truck members comprising a plurality of wheels and axles, and means including an equalizer mechanism for supporting said locomotive from said axles, said mechanism comprising equalizers for distributing the weight of said locomotive on said axles and coil springs and resilient shock absorbing units operating in parallel for absorbing shocks 70 75

incident to the running of the locomotive and preventing the same from reacting on said locomotive, said shock absorbing units comprising load supporting coil springs and friction elements 5 within said springs for yieldingly resisting the compression of said units, said units on certain of said truck members being vertically above the supporting axles of said truck members and the remainder being between the supporting axles 10 of certain other of said truck members.

2. In combination, a frame, a locomotive supported by said frame, a plurality of trucks, including a plurality of wheels and axles for supporting said frame, equalizer mechanism for supporting said frame from said axles, said mechanism comprising rigid equalizers fulcrumed on the frame between said axles, hangers connected to the ends of said equalizers and extending upwardly therefrom, rigid equalizer bars to which 20 adjacent hangers of adjacent equalizers are pivotally connected, saddle members for supporting said bars from said axles, and means comprising helical springs and cylindrical shock absorbing units between said saddle members and said bars for resiliently supporting said locomotive and for absorbing shocks delivered by said axles to said means through said saddle members, said means operating in parallel.

3. In combination, a locomotive, a frame for supporting said locomotive, a plurality of axles beneath said frame, equalizer mechanism for supporting said frame from said axles and for equalizing the weight of said locomotive on said axles, said equalizer mechanism comprising a plurality of rigid equalizer bars pivoted at their central portions to said frame at points between said axles, a hanger pivotally connected to each end of said equalizer bar, a plurality of rigid equalizer bars connected to said hangers, saddles 40 supported by said axles and extending upwardly therefrom, spring and shock absorber units interposed between said saddles and the second-named equalizer bars for absorbing shocks incident to the running of said locomotive, each of said shock absorbing units comprising friction members, means for forcing said members into frictional contact upon the compression of said unit, and resilient means for returning the parts to normal position after release, said spring units 45 consisting of helical springs.

4. In combination, a locomotive supporting frame, means including wheeled axles for supporting said frame, bearings for said axles, said means comprising a plurality of equalizer bars 55 pivoted at their central portions directly to said frame, a plurality of supporting members above said axles, hanger links between the ends of said bars and members, supports rigidly connected to said bearings and extending a material distance above said axles and supported thereby, and a plurality of springs and a load supporting friction shock absorbing unit between each of said supports and an intermediate portion of each of said supporting members, said units being 60 substantially in the vertical plane of the corresponding axles and constituting fulcrums for said member.

5. In combination, a frame, a locomotive supported on said frame, a plurality of trucks having 65 wheeled axles, equalizer mechanism including equalizer bars and connecting members for

equalizing the weight of said locomotive on said axles, means engaging said equalizing mechanism for supporting the same and said locomotive therefrom, said means comprising a plurality of spring assemblies, saddles supported by said 5 axles and in turn supporting said assemblies, each assembly comprising a plurality of helical springs, and a spring, friction unit, said unit comprising friction members, wedge elements for forcing said elements into frictional contact upon the compression of said unit and a spring for returning the parts to normal position after compression, said helical springs being more resilient and of less capacity than the conventional locomotive 10 springs, said springs and friction unit operating 15 in parallel.

6. In a locomotive, a frame, a plurality of wheeled axles, means including spring members and equalizing mechanism for supporting said frame from said axles and for equalizing the 20 load on the axles, said mechanism including a plurality of elements pivoted to said frame, a plurality of members pivoted to each other and to said elements, saddles extending upwardly above said axles, means including resilient members and spring units operating in parallel and engaging portions of said equalizing mechanism for supporting the same from said saddles, each unit comprising friction elements, wedging means 25 for forcing said elements into frictional contact, 30 and a spring for limiting the radial expansion of said friction elements and for returning the parts to normal position after release, said resilient members being more resilient and of less capacity than the conventional locomotive 35 springs.

7. In a locomotive, a frame, wheeled axles beneath said frame, journals for said axles, saddles secured to and extending above said journals, means including spring members and equalizing 40 mechanism mounted on said saddles for resiliently supporting said frame from said axles and for equalizing the load on said axles, said members comprising springs easily flexed and of smaller capacity than the conventional locomotive 45 springs and shock absorbing spring units, said units being located one above each saddle and constituting fulcrums for parts of said equalizing mechanism, each unit comprising a plurality of friction elements, wedges for forcing 50 said elements into frictional contact, and a spring for assisting in resisting the compression of said unit and for returning the parts to normal position after compression.

8. In a locomotive, a boiler, a truck frame 55 for supporting said boiler, wheeled axles for supporting said frame, bearing members for said axles, saddles extending upwardly from said bearing members, means for supporting the weight of said frame from said saddles and for 60 equalizing said weight on said saddles, said means comprising a system of equalizing bars, certain of which are pivoted directly to said frame, connecting members and resilient and shock absorbing units operating in parallel for supporting 65 said frame from said saddles, each of said shock absorbing units comprising a load supporting spring, a plurality of friction elements, and means for forcing said elements into frictional contact upon the compression of said unit. 70
